GOLF BALL RETRIEVER

Gregory C. Panek, 5831 N. Lacey Ave.,
Chicago, Ill. 60646

Filed Mar. 31, 1975, Ser. No. 563,632

Term of patent 14 years

Int. Cl. D21—02

U.S. Cl. D34—5 CB

FIG. 1 is a front elevational view of a golf ball retriever showing my design;

FIG. 2 is a top plan view such as would be seen along the sight line 2—2 of FIG. 1;

FIG. 3 is an end view of the retriever as would be seen along the line 3—3 of FIG. 1;

FIG. 4 is a rear elevational view of the retriever as would be seen along the line 4—4 of FIG. 3;

FIG. 5 is a bottom plan view as would be seen along the line 5—5 of FIG. 4;

FIG. 6 is an end view as would be seen along the line 6—6 of FIG. 1;

FIG. 7 is a front elevational view of a modified embodiment of the golf ball retriever;

FIG. 8 is a top plan view such as would be seen along the sight line 8—8 of FIG. 7;

FIG. 9 is an end view of the retriever as would be seen along the line 9—9 of FIG. 7;

FIG. 10 is a rear elevational view of the retriever as would be seen along the line 10—10 of FIG. 9;

FIG. 11 is a bottom plan view as would be seen along the line 11—11 of FIG. 10; and

FIG. 12 is an end view as would be seen along the line 12—12 of FIG. 1.

I claim:

The ornamental design for a golf ball retriever, as shown and described.
